United States Patent Office

Des. 231,868
Patented June 18, 1974

231,868

TOTE BAG

Matsusuke Ohyama, 1-25-24 OH-Imazato,
Osaka, Japan

Filed Oct. 13, 1972, Ser. No. 297,298

Term of patent 14 years

Int. Cl. D3—01

U.S. Cl. D87—5 G

FIG. 1

FIG. 3

FIG. 5

FIG. 2

FIG. 4

FIG. 1 is a perspective view of a tote bag embodying my new design;

FIG. 2 is a side elevational view showing the side opposite that seen in FIG. 1;

FIG. 3 is a top plan view thereof;

FIG. 4 is an end elevational view thereof, and

FIG. 5 is a bottom plan view thereof.

I claim:

The ornamental design for a tote bag, as shown.
